COMBINED PANIC DEVICE, HANDLE, AND LOCK HOUSING SET

William J. Horgan, Jr., 1299 Folkstone Drive,
Pittsburgh, Pa. 15213

Original design application Sept. 30, 1970, Ser. No.
25,284. Divided and this application Dec. 22, 1971,
Ser. No. 211,164

Term of patent 14 years

Int. Cl. D8—07

U.S. Cl. D8—138

Fig. 2

Fig. 3

Fig. 1

Fig. 5

Fig. 4

Fig. 7

Fig. 8

Fig. 6

Fig. 10Fig. 9FIG. 1 is a combined panic device, handle, and lock housing set embodying my new design shown in front elevation mounted on a door shown in phantom lines and partially broken away;

FIG. 2 is a top view of the embodiment shown in FIG. 1, shown mounted on the door which is shown in phantom lines;

FIG. 3 is a left side view of the embodiment shown in FIG. 1 shown mounted on the door which is shown in phantom lines;

FIG. 4 is a rear elevation of the embodiment shown in FIG. 1 shown mounted on the door which is shown in phantom lines;

FIG. 5 is a left side view of the embodiment shown in FIG. 4 (right side of the embodiment shown in FIG. 1) shown in phantom lines;

FIG. 6 is another combined panic device, handle, and lock housing set embodying my new design shown in front elevation mounted on a door shown in phantom lines and partially broken away;

FIG. 7 is a top view of the embodiment shown in FIG. 6, shown mounted on the door which is shown in phantom lines;

FIG. 8 is a left side view of the embodiment shown in FIG. 6 shown mounted on the door which is shown in phantom lines;

FIG. 9 is a rear elevation of the embodiment shown in FIG. 6 shown mounted on the door which is shown in phantom lines; and

FIG. 10 is a left side view of the embodiment shown in FIG. 9 (right side of the embodiment shown in FIG. 6) shown mounted on the door which is shown in phantom lines;

The door referred to in the description of various figures and shown in phantom lines forms no part of the design, but is included for illustrative purposes only to show the environment in which the panic devices are used.

This application is a division of my prior copending application Ser. No. D. 25,284, filed Sept. 30, 1970 which is incorporated herein by reference, and discloses and claims subject matter disclosed and claimed therein.

I claim:

The ornamental design for a combined panic device, handle, and lock housing set, as shown and described.
